JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

ROLLING AND CONTROLLING THE TEMPERATURE OF HOT METAL STOCK

Application filed August 3, 1925. Serial No. 47,789.

The present invention relates to improvements in rolling and controlling the temperature of hot metal stock. In the rolling of such stock, a wide range of temperature variation, particularly at or near the finishing end of the rolling operation, is highly desirable; for instance, the temperature of the stock while passing through the final or finishing rolls of a rolling mill determines, to a large extent, the physical characteristics of the rolled product, and for certain kinds of stock, as hereinafter described in detail, it is important to finish at a relatively low temperature. The invention resides in an arrangement and mode of operation of certain rolling mill instrumentalities whereby, when needed, any desired delay in the passage of the stock to the finishing rolls of a rolling mill may be readily secured, thus to control over a wide range the temperature at which said stock is finished preparatory to its passage onto a cooling bed,—while at the same time offering no obstruction to the operation of the mill at full capacity. In addition, absolute uniformity of temperature throughout each bar is secured, because that end of a bar which emerges first from a preceding stand of rolls, is invariably presented first to each succeeding stand of rolls. The above and other objects are attained by the method of rolling and by the arrangement of rolling mill apparatus hereinafter described with reference to the accompanying drawings, in which—

Fig. 1 is a plan view of one arrangement of apparatus embodying the invention.

Fig. 2 is a fragmentary elevational view on an enlarged scale, illustrating a part of the delay table shown in Fig. 1.

Fig. 3 is a transverse sectional view on an enlarged scale of said delay table, the section being taken on the line 3—3 of Fig. 1.

Fig. 4 is a plan view similar to Fig. 1, illustrating the same arrangement of apparatus, but with a delay table of different construction.

Fig. 5 is a sectional view on an enlarged scale, the section being taken on the line 5—5 of Fig. 4.

Fig. 6 is a sectional view on an enlarged

scale, the section being taken on the line 6—6 of Fig. 4.

Fig. 7 is a plan view of a modified arrangement of apparatus embodying the invention.

Like reference characters refer to like parts in the different figures.

In the arrangements shown in Figs. 1 and 4, the successive stands of rolls 1, 2 and 3 constitute, under certain circumstances, an ordinary looping mill, the rolls 1 and 3 running in the same direction, and the rolls 2 in the opposite direction, and the stands being closely grouped to facilitate, when desired, the operator's catching the first end of the stock and quickly introducing it to the successive roll passes, in the ordinary manner of operating looping mills. Such operation of the apparatus is made use of in rolling and finishing such stock as does not require any particular finishing temperature, and under these conditions, involving no delay in advance of finishing there is no obstacle to the operation of the mill at maximum capacity. Or if desired, while still operating the apparatus as an ordinary looping mill, a limited delay between the successive stands of rolls may be secured, by the operator's holding the first end of the bar emerging from the preceding stand before introducing it to the next pass, thus to increase the size of the loop that forms on the mill floor or table, as indicated by the differently-placed broken-line loops in Fig. 1.

In certain other kinds of stock, the oxidation which occurs in the finished product, as the result of finishing hot as above described, is extremely objectionable, and such stock must be finished at a lower temperature to prevent this oxidation; moreover, the reduction in temperature must occur near the end of the rolling process, or otherwise the cost of rolling would be very heavy. This applies particularly to thin stock of relatively wide flat cross section, such as used in the manufacture of leaf springs, this stock requiring finishing at as low a temperature as possible, but without allowing the cooling to proceed so rapidly as to produce brittleness. Certain other kinds of stock require finishing at certain definite temperatures in order to obtain a particular granular structure for the

rolled product, and to accomplish these various results, the rolling mill which produces these various products must be equipped, in advance of its finishing passes, with a very sensitive and easily adjusted temperature controlling apparatus.

One example of such apparatus for use in conjunction with the stands of rolls 1, 2 and 3, for the production of spring flats, is shown in Figs. 1, 2 and 3, the same disclosing the employment of a suitable guiding trough for receiving the stock run out lengthwise by the rolls 1, said trough preferably being made in two sections 4 and 5, with a pair of pinch rolls 6 introduced therebetween. An additional pair of pinch rolls 7 is preferably provided at the delivery end of the second trough section 5, and after passing through these rolls, the direction of movement of the stock is reversed, by its passage on edge through a turn-in repeater 8 of well known construction. From the latter the stock, in its passage to the rolls 2 is handled, as hereinafter described, on a delay table, and it will be understood that, for example, in the rolling of spring flats, the scale accumulating on the stock by its exposure for a greater or less period on said delay table, will be removed by passage through an edging pass provided by said rolls 2, following which said stock, after another reversal in its direction of movement, as shown at 9, will be finally finished and sized in a flat pass provided by the rolls 3.

Referring specifically to Figs. 1, 2 and 3, the delay table therein shown consists of a plurality of spaced cylindrical rollers 10, 10, constituting a longitudinal conveying means on which the stock, after making its turn of 180° in the repeater 8, resumes its normal flatwise disposition. In conjunction with the rolls 10, 10 are provided flat table sections 11, 11, the supporting surfaces of which are substantially flush with the tops of said rolls. Each roll 10 is mounted on a shaft 12, and the several shafts 12, 12 which extend beneath the table sections 11, 11 are adapted to be driven in unison from a common driving shaft 13 through the medium of suitable gearing 14, 14.

Along the opposite edge of the delay table, the sections 11, 11 are downwardly inclined, as shown at 15, Fig. 3, and adjacent thereto the shafts 12, 12 carry a series of aligned rollers 16, 16, having peripheral grooves 17 adapted to receive and support the stock on edge as it slides broadside down the inclines 15 into said grooves. For the broadside movement of the stock across the delay table, the sections 11, 11 have transverse slots or grooves 18, Fig. 2, for the guidance of a plurality of reciprocating push bars 19, 19. These push bars 19, 19 are movable in unison in any suitable manner; as shown in Fig. 3, each is connected, through an arm 20, to a common driving shaft 21 extending length-

wise of the delay table, and the oscillation of said shaft 21, as for instance by a suitable crank disk 22 and connecting rod 23, procures movement of the several bars 19, 19 in unison, to push the stock broadside across the delay table. The stroke of the pusher bars 19, 19 may be varied, and adjusted to any desired length, by providing suitable holes, as shown at 24, in the crank disk 22, or in the connecting rod 23, or in both; a pin 25, connecting these two members, may then be set to get any desired forward movement of the pusher bars 19, 19.

In the production, for example, of spring flats, the above described apparatus provides, in advance of the last two roll passes, a means for cooling the stock to any desired temperature, depending upon the duration of its sojourn on the delay table. On said delay table, each successive bar brings up, at its front end, against a suitable stop 26, and this contact is maintained during the broadside movement of said bar across said table until the bar slides off the incline 15 and is received by the grooved rollers 16, 16. As shown in Fig. 3, each bar, as received on the rollers 10, 10 of the delay table, comes under the action of the pushers 19, 19, and its resulting broadside movement is transmitted to a number of bars that have preceded it on said table, causing the first of these bars to slide off the incline 15. It is evident that the throw of the pushers 19, 19 may be adjusted so as to adapt the apparatus to bars of different widths, and also that by the adjustments provided, a wide variation in the time permitted to elapse between the delivery of the first end of a bar from the rolls 1 and the entry of said first end between the rolls 2 is afforded, thus keeping a complete and sensitive control on the temperature of the stock by controlling the duration of its stay on the delay table. In the rolling, for example, of spring flats, the scale resulting from oxidation during a greater or less exposure on said delay table is cracked off in the edging pass provided by the rolls 2, and then the bar is quickly brought to the desired form and size in the absence of rolled-in scale in the flat pass provided by the rolls 3.

The apparatus shown in Figs. 4, 5 and 6 provides the same general arrangement and affords exactly the same capabilities as the apparatus shown in Figs. 1, 2 and 3, the only difference being in the construction of the delay table. The latter, as here shown, consists of a plurality of table sections 27, between which are rotatably mounted a series of skewed conveyor rolls 28 to receive the stock from the first repeater 3; these rolls 28, having their axes of rotation displaced from lines normal to the longitudinal movement of the stock, are adapted to impart a combined longitudinal and broadside move-

ment to said stock as the latter is received thereon.

As best shown in Fig. 6, such broadside movement is normally resisted by a plurality of holding members 29, which extend upwardly through the table sections 27, so as to interpose positive obstructions to the side-wise movement of a bar as it is carried forward longitudinally against stop 26 by the rotation of the rolls 28. Each holding member 29 is secured to a rock shaft 30, and when the latter is oscillated, the members 29 move downward in unison, thereby to permit side-wise movement of the bar that is carried by the rolls 28; the oscillation of shaft 30 is effected in any suitable manner as, for example, by means of a link connection 31 to a connecting rod 32, the latter being actuated by a crank disk 33 on a shaft 34. When a bar on rolls 28 is released for sidewise movement as above described by depression of the members 29, said bar passes broadside off of the rolls 28 and onto a second series of skewed rolls 35 which, as best shown in Fig. 4, are arranged between the table sections 27 in alternating relation to the rolls 28.

The shafts 36 of the rolls 35, 35 are driven from a common drive shaft 37 through suitable gearing 38, 38 and the shafts 39, 39 of the rolls 28, 28 are also driven from the shaft 37 by gearing 40, 40. However, the respective sets of gearing 38, 38 and 40, 40 are arranged as shown, so that the rolls 35 will rotate very slowly in comparison to the rolls 28; this speed differential, coupled with the fact that the rolls 35 afford extended supporting surfaces, crosswise of the delay table, for the stock, allows a considerable number of bars to accumulate on said rolls during the broadside passage of one bar across the same. Thus a delay table constructed as shown in Figs. 4, 5 and 6 has substantially the same capabilities as the delay table illustrated in Figs. 1, 2 and 3. Each bar after its passage across the delay table shown in Figs. 4, 5 and 6 slides by gravity down the inclined portions 41, 41 of the table sections 27, 27, and is received on edge in the grooves 42, 42 of rollers 43, 43, the latter being mounted on the shafts 39, 39 of the rollers 28, 28; these rollers 43, 43 deliver the bars to the second stand of rolls 2 in precisely the same manner as the grooved rollers 16, 16 in the first described form of the invention.

Referring now to Fig. 7, a delay table which may be of the same construction as that shown in Figs. 1, 2 and 3 is here associated with a different arrangement of stands of horizontal rolls. Said stands of horizontal rolls 1^a, 2^a and 3^a are arranged in tandem, whereby they may be used, if desired, for continuous rolling. Or, if desired, the stock emerging from the rolls 1^a may be diverted and introduced edgewise to pinch rolls 44 for passage through the guiding trough 45, and

thence through another pair of pinch rolls 46, preparatory to having its direction of movement reversed in a repeater 47. From the latter said stock is received flatwise on the rolls 10, 10 of the delay table, and after bringing up against the stop 26 of said table, is transferred broadside across said table by the pushers 19, 19, the same as in the construction shown in Figs. 1, 2 and 3. The grooved rolls 16, 16 of said delay table deliver the stock on edge to edging or pinch rolls 48, and after passage through a repeater 49, the stock enters, successively, the aligned stands of horizontal rolls 2^a and 3^a. Thus, in all three forms of the invention, a wide range of temperature control, in advance of finishing, is secured, to suit varying thicknesses and kinds of stock.

I claim:—

1. In the rolling and finishing of hot metal stock, the improvement which consists in successively introducing the advancing front end of each piece to alternating flattening and edging passes, contained in a series of juxtaposed staggered roll stands running successively in opposite directions and operable, when desired, as a "looping" mill, and exposing each piece, in extended position, prior to introducing its advancing front end to the final edging pass, to a predetermined period of cooling.

2. In apparatus of the class described, a plurality of stands of rolls arranged in juxtaposition for operation as a looping mill, and including a stand of edging rolls which are driven in a direction opposite from preceding and succeeding stands of flattening rolls, a curved repeater remote from said preceding flattening rolls to direct the stock into the line of delivery of said edging rolls, a delay table interposed between said repeater and said edging rolls to receive said stock, and means associated with said delay table for delivering said stock to said edging rolls, by initial presentation to said edging rolls of that end of the stock which first emerged from said preceding flattening rolls.

3. In apparatus of the class described, a plurality of stands of rolls arranged in juxtaposition to provide a looping finishing mill, and including a stand of edging rolls running in a direction opposite to preceding and succeeding stands of flattening rolls, a loop return guide to reverse the direction of the stock between the preceding flattening rolls and said edging rolls, a delay table between said return guide and said edging rolls, on which table the stock is received flatwise, means for moving said stock broadside across said table, and means for thereafter delivering said stock from said table edgewise longitudinally to said edging rolls, by presentation to the latter of the same end which first emerged from said preceding flattening rolls.

4. The combination, with a series of juxtaposed rolling mill stands, arranged for

5. In the rolling and finishing of hot metal stock, by passage through a series of juxtaposed staggered rolling mill stands running successively in opposite directions and arranged for "looping" mill operation on pieces of stock of greater length than the distance between the roll passes, the improvement which consists in diverting such stock from its "looping" path toward an intermediate roll stand of said series, advancing the stock toward said intermediate stand in a longitudinally extended position, subjecting said stock, in said extended position, to a predetermined period of cooling, and thereafter delivering said stock to said intermediate stand by initial presentation thereto of the same front end of the stock which first emerged from the preceding stand of the series.
6. The combination, with a series of juxtaposed rolling mill stands arranged for "looping" mill operation on pieces of stock of greater length than the distance between roll passes, of means for subjecting the partially rolled stock, before passage through an intermediate stand of said series, to a predetermined period of cooling in a longitudinally extended position, said means comprising a delay table onto which said stock is delivered longitudinally from the stand preceding said intermediate stand, and means for delivering said stock from said delay table to said intermediate stand by presentation to the latter of the same front end of the stock which first emerged from said preceding stand.
7. In the rolling and finishing of hot metal stock, by passage successively through a series of juxtaposed roll stands arranged for "looping" mill operation on pieces of stock of greater length than the distance between the roll passes, the improvement which consists in diverting the stock on its way to an intermediate stand of said series, subjecting the diverted stock to a predetermined period of cooling in a longitudinally extended position, and thereafter, delivering said stock to said intermediate stand by initial presentation to the latter of the same front end of the stock which first emerged from the preceding stand of the series.
8. In a rolling mill, a series of juxtaposed roll stands presenting alternate flattening and edging passes, and adapted for "looping" mill operation on pieces of stock of greater length than the distance between said passes, in combination with a delay table disposed in approaching relation to the final edging pass of said mill, and adapted to support in extended position, for predetermined periods of cooling, the successive pieces of partially-rolled hot metal stock delivered by the preceding flattening pass of said mill, means for conducting the pieces delivered by said preceding flattening pass to that end of said table which is remote from said edging pass and for delivering said pieces longitudinally, by their first-rolled ends, to said table, and means for delivering each piece edgewise, by its first-rolled end to said edging pass, after a predetermined period of cooling on said table.
9. In the rolling and finishing of hot metal stock, the improvement which consists in diverting partially-rolled pieces of stock from their loop paths between successive juxtaposed roll stands of a "looping" mill, and delivering said diverted pieces successively, by their first-rolled ends to a delay table adapted to receive each piece in longitudinally extended position, exposing said pieces, as received successively on said delay table to uniform periods of cooling, and then delivering them edgewise, by their first-rolled ends to that roll stand of said "looping" mill from which they were diverted.
10. In a rolling mill, a pair of adjacent reducing roll stands between which successive pieces of stock undergoing reduction and of greater length than the distance between the roll passes, are free to form variable "loops," in combination with means disposed in approaching relation to the second of said adjacent stands for supporting each piece of stock in an extended longitudinal position, means for delivering each piece by its first-rolled end to that end of said supporting means which is remote from said second roll stand, and means for thereafter delivering each piece, after a predetermined sojourn on said supporting means, to said second roll stand, by initial presentation to the latter of said first-rolled end.

Dated this thirty-first day of July, 1925.
JEROME R. GEORGE.
